TEXTILE MACHINERY AND APPLIANCES
RELATING THERETOJoanny Jabouley, London, England, assignor, by
mesne assignments, to Celanese Corporation of
America, a corporation of DelawareApplication February 7, 1933, Serial No. 655,559
In Great Britain February 11, 1932

5 Claims. (Cl. 139—13)

This invention relates to circular looms, that is, looms in which the warps are arranged in a circle, and in which the weft is laid by means of a relative circular motion between the shuttle or shuttles and the warps. The invention is primarily concerned with the maintenance of even spacing of the warp threads, and proper presentation of the threads to the weft-inserting means.

Since in circular looms it is not convenient to employ a reed or its equivalent to beat up the weft in a manner similar to that of the oscillating reed of an ordinary loom, the warp threads are not subjected to the evening effect at the fell of the cloth obtained by a beat-up reed. In consequence, should there be any tendency to sideways displacement of the warps, there is nothing to overcome such tendency, and uneven fabric results.

According to the present invention, even spacing of the warps is provided by means engaging the warp threads in turn fairly near to the fell of the fabric, so causing the warps to vibrate and assume a correct position in the fabric. In looms in which the warp threads slide over the face of the shuttle, the vibration thus set up overcomes any tendency of the drag imposed by the friction between the warps and the shuttle from upsetting the warp spacing. Further, the vibration prevents the warps from sticking to each other during shedding.

Thus a finger may be arranged to penetrate the warps slightly just in advance of the lower edge of the shuttle. Further, in the case of shuttles provided with a feeling device in advance of their front edge, as for example the pivotally hung feeler described in U. S. application S. No. 655,561 filed February 7, 1933, a further finger may be arranged to cause those warps to vibrate which are just about to come into contact with the feeler. In this way, the warps are caused to divide freely into two sheets, thereby avoiding any slight jamming which might otherwise actuate the feeler and stop the weaving operation.

There may, however, be only one finger arranged to vibrate the warps just in advance of the feeler on the shuttle, this not only causing the warps to take up their correct position in the fabric but also preventing warps of the two sheets sticking together in shedding.

In some cases, especially with warp threads made of or containing artificial materials, it is advisable to have the finger engage the fabric itself as well as the warp threads adjacent to the fabric. In other cases, e. g. with heavy or strong warps, the finger may engage the warps only.

It appears probable that the effectiveness of the device according to the invention is due to the tensioned warps on release from the finger taking up a position of "least" resistance in the fabric, i. e. where they tend to cause the minimum of crinkling of the weft threads, and that this position obtains when the warps are evenly distributed round the fabric. The finger is effective both when the warps are arranged densely in the fabric and when they are (relatively) more widely separated, and thus renders possible the weaving of a wide variety of fabrics notwithstanding the absence of a spacing reed to even up the warps at beat-up.

The finger or fingers are preferably adjustable, both as regards their position relative to the shuttle or shuttles and the extent of their penetration of the warps. The fingers may also be adjustable as to height and angle.

The fingers may be used in circular looms in which the warps rotate as well as in those with stationary warps. In the case of rotating warps, a stationary finger may be used, the motion of the warps over the finger setting up the required vibration.

The invention will now be described in greater detail with reference to the accompanying drawing, which shows warp-vibrating fingers in a stationary shuttle loom of the type illustrated in U. S. application S. No. 655,560 filed February 7, 1933. It is to be understood that the following description is given by way of example only and is in no respect limitative.

Fig. 1 is a perspective view of the shuttle and the spacing fingers;

Fig. 2 is a diagrammatic view of the arrangement;

Fig. 3 shows in detail a form of single finger engaging both warps and fabric;

Fig. 4 is a plan view of the finger shown in Fig. 3; and

Fig. 5 shows the engagement of a single finger with the warps only.

In Fig. 1 is shown one of any convenient number of shuttles 10 mounted substantially vertically within the warp shed of a circular loom. Each shuttle 10 comprises a lower boat-shaped part carrying an upper frame 11 which is adapted to retain a weft spool 12. The weft spool 12 may carry a weft unwinding device 13 as described in U. S. application S. No. 655,558 filed February 7, 1933, the weft *d* being delivered near to the fell of the cloth through a channel in the rear of the shuttle and a guide 24 situated at the rear end of the bottom of the shuttle.

The shuttle 10 is held in position within the warp shed by means of vane wheels 14, 14 mounted on a rotatable shaft 15 outside the warps and extending into recesses 16 within the shuttle bodies. The shaft 15 is rotated at a suitable speed by gearing connected to the drive of the loom (not shown) so that as the rotating warps meet the vane wheels 14, 14 the warps are divided into groups by the vanes and pass through the spaces between the vanes, so having a substantially uninterrupted motion while the shuttles 10 are held stationary. Each shuttle carries a warp feeling device 17 of the type described in U. S. application S. No. 655,561, which device is adapted to impel a horizontal rod 18 rearwardly on breakage or jamming of the warp threads, so as to actuate mechanism by which the shuttles are caused to rotate with the warps.

The lower boat-shaped part of the shuttle 20 tapers to a narrow edge 19 which rests on the fell of the cloth, serving to beat-up the weft laid by the preceding shuttle.

Just above the fell of the cloth a finger 20 is adjustably mounted on a peg 22 upstanding from a plate 21 which is adjustably mounted on a convenient part of the loom. The finger 20 terminates just in front of the lower edge 19 of the shuttle. An auxiliary spring finger 23 is carried by the finger 20 and is adjusted so as to engage those warp threads about to engage the feeler 17. The two fingers may be moved towards or away from the shuttle and can also be adjusted as to height and direction by reason of their adjustable mounting, to suit all types of warp threads and to impart more or less severe or light vibration to the threads as required.

In operation, the warp threads *a* which after shedding may bunch or cling together are engaged by the spring 23 (Fig. 2) and are vibrated so as not to jam against each other as they commence to divide to form a shed in advance of the feeler 17. The two sheets of warp threads *b*, *c* then pass to the two sides of the shuttle and the finger 20 penetrates the sheet *c* to a small extent so that just as these warps commence to slide along the outside of the shuttle, they are vibrated and pass easily into the spaces of the vane wheels 14. Thus any thread bunches are broken up and the even spacing of the warps is maintained.

Figs. 3 and 4 show a single finger 25 situated in advance of the shuttle bottom 19 (at about the position of the supplementary finger 23 of Figs. 1 and 2) and at the level of the fabric *e*. Thus both the fabric *e* and the warps *a* are engaged by the point 26 of the feeler 25, Fig. 3 showing how the warps are held back at the point of the feeler and then released as they pass beyond it.

Fig. 5 is a view similar to Fig. 4, but showing a feeler 27 engaging the warps *a* only, thus pulling them back at its point 28. This figure also en-

ables it to be seen how the warps are slightly deflected in the edge of the fabric (see 29) and then released to assume an even spacing.

What I claim and desire to secure by Letters Patent is:—

1. In a loom having warps arranged in a circle, means between which and the warps there is relative motion, said means being so disposed as to penetrate the normal line of the warp threads and, because of the relative motion, to engage and pluck the warp threads in turn, the resultant vibration causing the warp threads to assume an even spacing in the fabric woven in the loom.

2. In a loom having warps arranged in a circle, means between which and the warps there is relative motion, said means being so disposed as to penetrate the normal line of the warp threads near the fell of the fabric, and, because of the relative motion, to engage and pluck the warp threads in turn, the resultant vibration causing the warp threads to assume an even spacing in the fabric woven in the loom.

3. In a loom having warps arranged in a circle, means between which and the warps there is relative motion, said means being so disposed as to press against the fell of the fabric and to penetrate the normal line of the warp threads adjacent thereto simultaneously and, because of the relative motion, to engage and pluck the warp threads in turn, the resultant vibration causing the warp threads to assume an even spacing in the fabric woven in the loom.

4. In a loom having warps arranged in a circle, means between which and the warps there is relative motion, said means being so disposed as to penetrate the normal line of the warp threads and, because of the relative motion, to engage and pluck the warp threads in turn, the resultant vibration causing the warp threads to assume an even spacing in the fabric woven in the loom.

5. A loom having warps arranged in a circle, comprising means adapted to divide the warp threads into a shed, a shuttle adapted to be supported within the shed, a pair of fingers between which and the warp threads there is relative motion, the first finger being so disposed as to engage the warp threads near the point at which they are divided into a shed by said shedding means, and the second finger being so disposed as to engage the threads immediately in advance of the shuttle, said fingers serving to pluck the warp threads in turn by reason of the relative motion, the vibration resulting from the plucking of the threads by the first finger preventing the warp threads jamming as they commence to divide to form a shed, and the vibration resulting from the plucking of the threads by the second finger causing the warp threads to assume an even spacing in the fabric woven in the loom.

JOANNY JABOULEY.
